UNITED STATES PATENT OFFICE.

CLAUDE E. PIERCE, OF TACOMA, WASHINGTON.

ENVELOPE.

1,402,650.

Specification of Letters Patent. Patented Jan. 3, 1922.

Application filed February 7, 1919. Serial No. 275,592.

To all whom it may concern:

Be it known that I, CLAUDE E. PIERCE, a citizen of the United States, residing at Tacoma, in the county of Pierce and State 5 of Washington, have invented new and useful Improvements in Envelopes, of which the following is a specification.

This invention relates to new and useful improvements in envelopes and the principal object of the invention is to provide improved means for holding the envelope in closed condition.

Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the several views, and in which:—

Figure 1 is a view of the blank from which the envelope is made.

Figure 2 shows the envelope in partly closed position.

Figure 3 shows the envelope with the top flap open.

Figure 4 shows the envelope closed.

Figure 5 is a sectional view of one of the rivets.

As shown in these views the envelope consists of the front 1, the bottom flap 2, the end flaps 3, and the top flap 4. The end flaps are made of rectangular form with the side extension 3', said side extensions having their inner ends flaring, as shown. A crease is formed at the junction of the extensions with the end flap so that said extensions may be folded upon the end flap after the end flap is folded over upon the front. These 45 end flaps and their extensions are perforated and the perforations are so located that they will register with each other when in folded condition.

The end flap 2 is provided with a small

flap 2' on each of its inclined sides and with 55 a pair of holes 2" which are so located that they will register with the holes in the end flaps and their extensions when the envelope is closed. Both sides of the small flaps 2' are provided with adhesive and these end flaps 2' are adapted to fold over and be stuck to the lowermost extension flaps. The extreme ends of the end flaps and their extensions are also to be glued together at their outer ends as shown.

The top flap 4 is provided with the small flaps 4', each of which is located on one of the three sides of said top flap. In the adjoining ends of these flaps 4' are formed perforations which register with each other 70 as shown and when the top flap is folded over into closed position these perforations will register with the perforations before described.

In forming the envelope the end flaps with 75 their extensions are folded over. The extensions are folded upon the outer side of each end flap as shown in Figure 2 and their ends glued together. Then the small flaps 2' are folded over upon the bottom flap and 80 secured thereto by the adhesive. The adhesive carried by the outer faces of these flaps 2' is moistened and then said bottom flap is folded over upon the end flaps and their extensions. One member 5 of a snap 85 button 6 is then placed through each set of perforations. The other member 7 of each button being placed under the small flaps 4' of the top flap, the opening in said member 90 registering with the perforations in said flap 4' so that when the top flap is folded over the member 7 will engage the member 5 and by pressing upon the two members said members will be sprung together and thus 95 hold the envelope in closed position. Before folding the upper flap the adhesive carried by the flaps 4' is moistened so that said flaps will stick to the lower flaps. In this way the envelope is held in closed position 100 by the adhesive and the snap buttons. The envelope is of great strength due to the reinforcement of the flap by the extensions and small flaps.

It is thought from the foregoing description that the advantages and novel features 105 of my invention will be readily apparent.

I desire it to be understood that I may make such changes in the construction and

in the combination and arrangement of the several parts, provided that such changes fall within the scope of the appended claims.

Having described my invention what I claim and desire to secure by Letters-Patent is:

1. An envelope comprising end flaps and top and bottom flaps, said bottom flap having small flaps at its end edges which are turned over and have adhesive on their outer faces, the top flap having small turned over flaps at its ends and at its top edge, the outer faces of which are coated with adhesive, extensions formed on the sides of the end flaps and adapted to be folded over upon the outer face of said end flaps and upon which the small flaps on the bottom flap are secured, a male part of a fastener carried by each end flap and passing through the bottom flap and a pair of female parts carried by the overlapping ends of the small flaps of the top flap and adapted to engage the male parts when the envelope is closed.

2. An envelope comprising a body, end

flaps thereon having auxiliary extensions projecting from their sides and foldable over the outer face thereof, adhesive for securing the extensions in folded position on the outer face of the end flaps, top and bottom flaps, the bottom flap having extensions on its end edges provided with adhesive on inner and outer sides thereof, said latter extensions being foldable and secured to the inner side of the bottom flaps, flap extensions on the end and upper edges of the top flap, said extensions having adhesive on the inner and outer surfaces thereof and adapted to overlap each other, a fastening device passing through the overlapped portions of said flap extensions, and co-acting fastening devices passing through the end flaps and their extensions, the adhesive on the outer faces of the extensions on the top and bottom flaps adapting the same to be secured to the end flaps as and for the purpose described.

In testimony whereof I affix my signature.

CLAUDE E. PIERCE.
